CLAIM

The ornamental design for wheel for automobile as shown and described.

DESCRIPTION

1. Wheel for automobile

1.1 : Perspective

1.2 : Front

1.3 : Back

1.4 : Left

1.5: Right

1.6 : Top

1.7: Bottom

1.8 : Rear perspective

Reproduction 1.1 is a perspective view of a wheel for automobile showing our new design; reproduction 1.2 is a front elevation view thereof; reproduction 1.3 is a rear elevation view thereof; reproduction 1.4 is a left side elevation view thereof; reproduction 1.5 is a right side elevation view thereof; reproduction 1.6 is a top plan view thereof; reproduction 1.7 is a bottom plan view thereof; reproduction 1.8 is a rear perspective view thereof.
